PLAYGROUND CLIMBER REPRESENTING A SEA SERPENT

Robert S. Wormser, Hillsdale, Mich., assignor to Game
Time, Inc., Litchfield, Mich., a corporation of Michigan

Filed Dec. 30, 1968, Ser. No. 15,139

Term of patent 14 years

Int. Cl. D21—03

U.S. Cl. D34—5

FIG. 1

FIG. 2

FIG. 4

FIG. 1 is an elevational view of the left side of a playground climber representing a sea serpent in accord with my new design, the right side being identical thereto,
FIG. 2 is a top plan view of my new design,
FIG. 3 is a front, elevational view, and
FIG. 4 is a rear, elevational view.

I claim:

The ornamental design for a playground climber representing a sea serpent, substantially as shown and described.
